UNITED STATES PATENT OFFICE

2,350,706

WINDOW SASH STOPPING DEVICE

Daniel G. Sell, Kansas City, Mo.

Application September 1, 1943, Serial No. 500,815

3 Claims. (Cl. 292—288)

The invention relates to window sash stopping devices and has for its object to provide a device of this kind comprising a U-shaped body member adapted to be received on the inside strip of a window frame and having one of its arms provided with a clamping screw and its other arm provided with integral upwardly and inwardly extending piercing arms for engaging the inner side of the inside strip and also with a hingedly mounted piercing arm adapted to engage the adjacent side of the parting strip and to position the arm of the U-shaped frame with its piercing member and hinged piercing member in the path of the upper rail of the lower sash so that the device will limit the upward movement of the sash by unauthorized persons seeking entrance to the room.

A further object is to provide a sash limiting device comprising a U-shaped frame adapted to arch and be clamped on the inside strip of a window frame, and to pierce parts in a manner whereby the opening of the sash can be limited.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of the sash limiting device.

Figure 2 is a vertical transverse sectional view through a portion of the upper and lower sash, showing the device applied to the window frame between the inside and parting strips.

Figure 3 is a top plan view of the device.

Figure 4 is a perspective view of a modified form of the device wherein the hinged piercing member engages the side stile of the upper sash for limiting the downward movement thereof.

Referring to the drawing, the numeral 1 designates the inside strip of a conventional form of window frame, and 2 the parting strip. Slidably mounted between the strips 1 and 2 is a lower sash 3 having a top rail 4. Travelers have a great deal of trouble ventilating rooms, and at the same time exclude unauthorized persons from further opening the window. To obviate this difficulty the sash limiting device is provided, and the device comprises a U-shaped body member 5 having right angle arms 6 and 7. The body member 5 arches the inside strip 1 and the arm 7 extends into the lower sash channel 8. Arm 7 terminates

in an upwardly and inwardly extending piercing arm 9 which is placed in engagement with the inner side 10 of the inside strip 1 and embeds in the outside strip when the thumb screw 11 carried by the arm 6 is tightened against the inside strip. After the U-shaped body member 5 is placed in position the hinged piercing member 12 is positioned to pierce as at 13 the adjacent side of the parting strip 2.

After the sash 3 has been adjusted for proper ventilation of the room the device is placed in position above the sash. If an unauthorized person attempts to raise the sash 3 for entering the room the sash rail 4 will engage the arm and will further embed the piercing members 9 and 12, thereby preventing sash from being opened. The piercing member 12 is provided with an eye 14 which encircles the arm 7, preferably between lugs 15 which lugs maintain the piercing member 12 in position, however it is to be understood that lugs 15 may be eliminated so that the piercing members can be used, particularly the member 12 against the parting strip or against the side stile of the upper sash 16.

Referring to the modified form shown in Figure 4, the operation is substantially the same, however the curved piercing member 17 is longitudinally adjustable on the arm 7 so that it can cooperate with the parting strip 2 or with the side stile of the upper sash 16, therefore it will be seen that the upper sash will be held against downward movement, and the lower sash limited in its upward movement.

From the above it will be seen that a window sash limiting device is provided which is simple in construction, and one which is compact and may be easily transported from place to place and adjusted in position on conventional window frames. It will also be seen that the device may be cheaply manufactured and sold.

The invention having been set forth what is claimed as new and useful is:

1. A sash limiting device adapted to be attached to the inside strip of a window frame and to limit the movement of a sash in the channel between the inside strip and the parting strip, said device comprising a U-shaped body member arching the inside strip, one arm of said U-shaped member overlying the outer side of the inside strip, the other arm of said body member extending into the sash channel between the inside and parting strips, said last named arm being provided with an integral piercing member adapted to engage the inner side of the inside strip, a set screw carried by the first mentioned arm of the

body member and adapted to engage and pierce the inside strip and a hinged piercing member hingedly mounted on the arm between the inside and parting strips and adapted to pierce the parting strip, said piercing members being in the path of the sash.

2. A device as set forth in claim 1 wherein the hinged piercing member is longitudinally shiftable on the arm between the inside strip and part-

ing strip, whereby the hinged piercing member may be placed to engage the parting strip or the side stile of the upper sash.

3. A device as set forth in claim 1 including means on the arm between the inside and parting strip for limiting side movement of the hinged piercing member.

DANIEL G. SELL.
